SIGHT FOR DIVE BOMBING

Maurice E. Browder, United States Navy, and
Albert Wertheimer, Washington, D. C.

Application June 21, 1935, Serial No. 27,798

13 Claims. (Cl. 33—46.5)

(Granted under the act of March 3, 1883, as
amended April 30, 1928; 370 O. G. 757)

1

This invention relates to bomb sights used in dive bombing. It is the object thereof to provide a sight which will continuously generate the correct line of sight to the target irrespective of the maneuvering of the bomber.

In the drawings:

Figs. 1 and 2 show diagrammatically the relations existing among the several factors involved in dropping the bomb during the dive;

Fig. 3 illustrates an elementary form of a 10 device embodying the principles of our invention.

Fig. 4 shows one embodiment of our invention;

Fig. 5 is a plan view of the coils in the gyroscopic follow-up system.

Fig. 6 illustrates schematically a gyroscopic 15 control usable with our invention; and

As long as bombing is done at low altitudes in very steep dives, even point blank aiming may result in some hits on the target. However, as the art of defense against dive bombing progresses, higher altitudes must be used and it becomes necessary to have some sort of sighting device to make the bombing successful.

In Fig. 1 the line OH is horizontal, the line O'O represents the altitude of the line OH above the ground, the line OP represents the axis of a diving plane and the line OT is the line of sight from point O to the target T. (In the discussion of this figure it is assumed that the flight path and the axis of the plane coincide.) If the plane is at the altitude O'O' at the instant the bomb is released, then the distance O'T is the horizontal distance traveled by the bomb during its fall and the line OT is the line of sight. The distance O'T depends on the speed of the plane, on the altitude, and on the angle of dive. In order that the bomb shall strike the target T the angle between the vertical and the line of sight must be equal to arctangent O'T/O'O, which is not the same as the angle of dive. Thus the line of sight must be inclined at a certain angle to the axis of the plane and it is the function of our invention to generate this angle correctly for all conditions of speed, altitude, and dive angle.

Actually, when a plane is diving, the flight path does not coincide with the axis of the plane, and this must be taken into account in computing the line of sight with reference to the axis of the plane. In Fig. 2 are shown the factors that must be considered and as represented therein:

O'O' is the altitude at release of the bomb;
O'T is the horizontal distance passed over by the bomb during its fall;
OS is the flight path, that is, the line actually followed by the plane;

2

OP is the axis of the diving plane;
OT is the line of sight to the target;
D is the dive angle, that is, the angle between the vertical and the flight path;
5 C is the lift angle, that is, the angle between the plane and the flight path.
B is the sight angle, that is, the angle between the line of sight and the axis of the plane; and,
A is the angle of inclination, that is, the angle between the axis of the plane and the vertical.

Let the speed of the plane along the flight path be denoted by V and the altitude by Y.

If the effects of air resistance are neglected, the sight angle for a drop in vacuo is given by:

(1) $B = D - C - \text{Arctan}$

$$\left(\frac{V \sin D}{gy} \sqrt{V^2 \cos^2 D + 2gY} - V \cos D \right)$$

20 where g is the acceleration due to gravity.

If the effects of air resistance are to be taken into account the sight angle is given by:

(2) B equals F(Y, V, D, C), where F is some function, not however a closed function, but one 25 that has to be determined and evaluated separately for each set of conditions, Y, V, D, and C, by integrating numerically two simultaneous differential equations.

Even if it were mechanically feasible to construct a mechanism which would generate the sight angle in accordance with (1) or (2), it would necessarily be extremely complicated and entirely impracticable for use in a plane intended for dive bombing.

35 After actual computations of the sight angle from (2) for the range of the variables of practical importance, it was found that the results of such computations could be expressed with sufficient precision by an empirical formula of the form:

(3) $(B - L) = K(A - L)$, where L is the lift angle for a vertical dive and is constant for any type of plane, while K is a factor which depends only on the speed and altitude, is constant for any given set of conditions, and is independent of the other variables. All angles are vectors reckoned positively from the axis of the plane in the counterclockwise direction. The present invention is based upon the empirical formula discovered, and includes the provision of means for establishing a vertical, and thus determining the angle A from which can be derived the angle (A - L). The means for sighting at the target is initially offset above the axis of the plane by the angle L and is actuated by the mechanism

to generate the angle $(B-L)$. The ratio K between $(A-L)$ and $(B-L)$ is varied according to speed and altitude.

In Fig. 3 the straight edge 7 which is fixed to a rotatably mounted disc 8, has a limiting position counterclockwise from the perpendicular to the axis of the plane by an angle equal to the angle L . Gear teeth 9 cut in a portion of the periphery of disc 8 are meshed with the teeth of a rack 10 that is slideable between guides 11. The straight edge 12, which is used for sighting at the target, is fixed to a disc 13 having teeth 14 meshed with the teeth of rack 15 that is slideable in guides 16, the diameter of discs 8 and 13 being equal. Link 17 is mounted on a pivot 18 adjacent its lower end and has formed in it the slots 19 and 20 the pin 21 carried by rack 10 being slideable in the former slot and pin 22 on rack 15 being slideable in the latter slot. Since the diameters of the two discs are the same, it follows that the angle through which straight edge 12 is turned when driven by rotation of the disc 8 is dependent upon the ratio of the distance between pivot 18 and pin 22 to the distance between pivot 18 and pin 21, and the link 17 may be calibrated to show the position of pin 22 in slot 20 to cause the straight edge 12 to pass through an angle equal to any desired fraction of the angle through which straight edge 7 is turned.

The straight edge 12 has an initial limiting position above the axis of the plane by the angle L . Therefore, when the pin 22 is set to a position determined by the ratio factor K the angular movement of 12 will be equal to $(B-L)$ when the straight edge 7 is turned through the angle $(A-L)$. This type of sight is intended for use in a two-seater plane. When the plane dives at an angle A the straight edge 7 will be rotated from its initial position through a scalar angle equal to 90° minus A , by the dive of the plane, and when the operator rotates the straight edge to make it horizontal he must necessarily turn it through a scalar angle $(A+L)$, which is a vector angle $(A-L)$ as above defined. The pin 22 being set at the proper position for the given altitude and air speed, the straight edge 12 will be rotated by the linkage through a vector angle $(B-L)$ when the operator moves straight edge 7 to the horizontal and thus will be set at the correct line of sight.

While, for purposes of illustration, the sighting elements are shown in the form of straight edges, it is to be understood that any suitable type of sighting device may be used in their stead.

In Fig. 4 the several parts described in Fig. 3 are given the same reference characters, but it is to be understood that Fig. 3 was largely schematic while Fig. 4 discloses a convenient mechanical embodiment of our invention. Instead of having a rack 15 which directly engages both the link 17 and the disc 13, we prefer to use a rack 23 connected to the disc 13 with a one-to-one ratio by means of gears 24 and 25 and a shaft 26 which may be flexible or otherwise, as is most convenient with respect to the locations of the several parts. The rack 23 has at one end a transversely elongated portion 27 having in it a slot 28 in which is slideable the pin 29 carried by a slide 30 mounted in a member 31 that is slideable in guides 32, the slide 30 being connected to link 17 by means of pin 33 in slot 20. It will, of course, be understood that pins 29 and 33 are separated by such a distance that there will be no likelihood of the elongated portion 27 contact-

ing the link 17 when the latter is swung on its pivot 18. The rod 34 is connected to member 31 at one end and is threaded at its opposite end to engage the threads in the member 35 upon which are rotatably mounted the pinions 36 of a differential gear carried by a frame 37. Meshed with the pinions 36 are gears 38 and 39, the gear 39 being connected to a knob 40 which is calibrated in altitudes and the gear 38 similarly connected to a knob 41 calibrated in miles per hour air speed. The frame 37 is fixed, and, therefore, rotation of either of the knobs 40 and 41 will cause the pinions 36 to travel around the rod 34 and thereby shift the rod lengthwise of itself, thus moving the member 31 in the slides 32. It is apparent that the movement imparted to rod 34 when the knobs 40 and 41 are simultaneously rotated will be the result of the algebraic sum of their rotations. The ratios between pinions 36, and pinions 38 and 39, and the pitch of the thread on rod 34 are such that the member 31 will be set to the correct position in slides 32 to cause the desired proportional angular movement of straight edge 12 when straight edge 7 is rotated.

The mode of operation is as follows:

It having been decided from what altitude and at what air speed the bombs are to be dropped, the member 31 is set in the position corresponding to the chosen speed and altitude. After the dive has been begun the operator rotates the straight edge 7 into parallelism with the horizon determined by sighting transversely across it (thus eliminating the effect of dip), and he thereafter keeps it so sighted until the attack has been completed. As above explained, this movement of straight edge 7 through the angle $(A-L)$ causes the straight edge 12 to generate the angle $(B-L)$, which gives the correct angle B between the axis of the craft and the line of sight to the target and angle $(B-L)$ is varied in conformity with any changes in the dive angle due to the fact that sighting device 7 is kept horizontal. The pilot then directs the plane toward the target, keeping the straight edge 12 sighted at the objective and when the chosen altitude has been reached, the bomb is released and the plane is pulled out of the dive.

We have also provided means for adapting our invention to single seater planes by equipping them with the automatic control mechanism shown in Figs. 5 and 6. The gyro wheel 42 is rotatably mounted in the ring 43 which is carried on gudgeons 44 that are journaled in a cardan 45 that in turn is pivotally mounted in a supporting bracket 46, the axis of rotation of the gyro and the pivotal mountings of ring 43 and cardan 45 being mutually perpendicular. A coil 47 is fixed on ring 43 coaxially with the gyro and is energized by alternating current supplied through wires 48. A bail 49 is pivotally mounted on bracket 50 and carries two coils 51 and 52 that are spaced from each other and normally lie in positions that are symmetrical with respect to coil 47. The coils 51 and 52 are connected to separate amplifiers carried in a case 53, the return from the amplifiers to the two coils being through the common wire 54. As long as the craft is traveling horizontally, the coils 51 and 52 are symmetrically disposed with respect to coil 47 and have induced in them equal and opposite voltages, and therefore the outputs of the two amplifiers annul each other and produce no torque in motor 55 whereof the field is energized by direct current through wires 60 and to the

armature of which the amplifiers are connected by wires 53. However, when the plane dives, the axis of spin of the gyro remains vertical and the bail 49 being connected to the structure of the plane is moved with respect to coil 47 which moves coils 51 and 52 from their position of symmetry and increases the voltage induced in one of the coils and simultaneously weakens the voltage induced in the other, with a corresponding increase in the output of one of the amplifiers and decrease in the output of the other thereof. Since the currents supplied to motor 55 are no longer equal and opposite, a resultant torque is produced which operates the motor. Through worm 57 on the shaft of the motor and gear 53 fixed on a pivot of bail 49 and meshed with worm 51 the bail is rotated upon its pivots and thereby turns the gear 59 which is secured on the other pivot of bail 49 and is meshed with the rack 10. The angle (A-L) is thus automatically put into the mechanism to actuate the link 17 and so cause the straight edge 12 to generate the angle (B-L).

The invention described herein may be manufactured and used by or for the Government of the United States of America for governmental purposes without the payment of any royalties thereon or therefor.

We claim:

1. A dive bombing sight for aircraft, comprising a rotatably mounted sighting arm having a limiting position at an angle above a line through the center of rotation of said arm and parallel to the axis of the craft equal to the lift angle of the craft when in a vertical dive; a horizon arm rotatable to sight the horizon, said horizon arm having a limiting position backward from a line perpendicular to the axis of the craft equal to the said lift angle; a first gear-toothed element connected to said horizon arm to rotate therewith and a second like element connected to said sighting arm to rotate therewith, a first rack meshed with said first element, a link pivoted at one end and provided adjacent the opposite end with a short longitudinal slot and with a second longitudinal slot extending from adjacent said pivot past the center of said link, a pin carried by said first rack extending into said short slot, a pair of guides lying at right angles to said first rack and on opposite sides of said link, a member slidible in said guides, a slide carried by said member to be movable longitudinally of said member, a pin on said slide extending into said second slot, a second rack having a slotted transversely extending portion at one end, a second pin on said slide disposed in the slot in said second rack, a one-to-one ratio driving connection between said second rack and said second element, and means to move said member to a position in said guides determined by a function of a chosen altitude and the air speed of the craft.

2. A dive bombing sight for aircraft, comprising a sighting device mounted for rotation in the vertical plane of its longitudinal axis, and having a limiting position somewhat above a line parallel to the axis of the craft, a horizon sighting device mounted for like movement and having a limiting position slightly back of the perpendicular to the axis of the craft, means connecting said two devices whereby movement of the latter moves the former, said means including an adjustable ratio linkage to cause the angular movement imparted to said sighting device from said horizon sighting device to be a predetermined proportion of the angular movement of said horizon sighting

device, and in the same angular sense, and means to adjust said linkage to operate proportionally to a function of a predetermined air speed and also to a function of a predetermined altitude.

3. A dive bombing sight for aircraft, comprising a sighting device mounted for rotation in the vertical plane of its longitudinal axis, and having a limiting position somewhat above a line parallel to the axis of the craft, a horizon sighting device mounted for like movement and having a limiting position slightly back of the perpendicular to the axis of the craft, means connecting said two devices whereby movement of the latter moves the former, said means including an adjustable ratio linkage to cause the angular movement imparted to said sighting device from said horizon sighting device to be a predetermined proportion of the angular movement of said horizon sighting device and in the same angular sense, and means including a differential gear to adjust said linkage to operate proportionally to a function of a predetermined air speed and also to a function of a predetermined altitude.
4. A dive bombing sight, comprising a first sighting device angularly movable in a vertical plane for sighting a target, a second sighting device likewise movable for sighting the horizon, the first said device having a limiting position offset above a line parallel to the axis of the craft by an angle equal to the lift angle of the craft when in a vertical dive, and the second said device being offset back of the vertical to said axis by an equal angle, and an adjustable ratio linkage operatively connecting the said devices, said linkage being settable to operate in accordance with a function of a predetermined air speed and a function of a predetermined altitude.
5. A dive bombing sight, comprising a first sighting device angularly movable in a vertical plane for sighting a target, a second sighting device likewise movable in said plane for sighting the horizon, and an adjustable ratio linkage operatively connecting the said devices, said linkage being settable to operate in accordance with a function of a predetermined air speed and a function of a predetermined altitude.
6. A dive bombing sight, comprising a sighting device angularly movable in a vertical plane for sighting a target, an adjustable ratio linkage operatively connected to said device, means to set said linkage to cause the movement imparted to said device to be a function of a predetermined air speed and also a function of a predetermined altitude, and gyroscopically controlled means to impart to said sighting device through said linkage a movement that is a function of the angle of inclination of the axis of the craft to the vertical.
7. A dive bombing sight, comprising a sighting device angularly movable in a vertical plane for sighting a target, an adjustable ratio linkage operatively connected to said device, means to set said linkage to cause the movement imparted to said device to be a function of a predetermined altitude, and stabilized means to impart to said sighting device through said linkage a movement that is a function of the angle of inclination of the axis of the craft to the vertical.
8. A dive bombing sight, comprising a sighting device angularly movable in a vertical plane for sighting a target, an adjustable ratio linkage operatively connected to said device, means to set said linkage to cause the movement imparted to said device to be a function of a predetermined air speed and also a function of a predetermined

altitude, and automatic means to impart to said sighting device through said linkage a movement that is a function of the angle of inclination of the axis of the craft to the vertical.

9. A dive bombing sight, comprising a first sighting device angularly movable in a vertical plane for sighting a target, a second sighting likewise movable for sighting the horizon, means interconnecting said devices to move said first sighting device through an angle equal to the angle between the axis of the craft and the correct line of sight to a target plus the lift angle of the craft in a vertical dive while the second sighting device is moved through an angle that is equal to the angle of inclination of the axis of the craft to the vertical plus the said lift angle, the said means being adjustable to vary in accordance with a function of a chosen air speed and a chosen altitude the angle through which the first said device is moved.

10. A dive bombing sight, comprising a sighting device for sighting a target, gyroscopically controlled means to move said device through an angle equal to the angle between the axis of the craft and the correct line of sight to a target plus the lift angle of the craft when in a vertical dive, and means to adjust the first mentioned means to vary in accordance with a function of a chosen air speed and a chosen altitude the angle through which said sighting device is moved.

30

11. A dive bombing sight, comprising a sighting device for sighting a target, stabilized means to move said device through an angle equal to the angle between the axis of the craft and the correct line of sight to a target plus the lift angle of the craft when in a vertical dive, and means to adjust the first mentioned means to vary in accordance with a function of a chosen air speed and a chosen altitude the angle through which said sighting device is moved.

12. A dive bombing sight, comprising a sighting device for sighting a target, automatic means to move said device through an angle equal to the angle between the axis of the craft and the correct line of sight to a target plus the lift angle of the craft when in a vertical dive, and means to adjust the first mentioned means to vary in accordance with a function of a chosen air speed and a chosen altitude the angle through which said sighting device is moved.

13. Dive bomb sighting means comprising a straight edge sighting member adapted to be maintained with its length parallel to the horizon, a second sighting member for sighting at a target, adjustable linkage means connecting said sighting members, and means to change the ratio of said linkage proportionately to a function of an air speed and an altitude.

MAURICE E. BROWDER.
ALBERT WERTHEIMER.
